DS. 2284

P. Bradford, of New Haven, Conn.

Assignor to

Sargent & Company, of the same place

Letters Patent No. 22044, Dated Mar. 27, 1866.

Design for a coffin handle.

The schedule referred to in the Letters Patent and making part of the same,

To all whom it may concern:

Be it known that I, P. Bradford, of New Haven in the County of New Haven and State of Connecticut, have invented a new Design for Coffin Handles, and do hereby declare the following, when taken in connection with the accompanying drawings and the letter of reference marked thereto, to be a full, clear and exact description of the same, and which said drawings constitute part of this specification, and represent:

Figure 1, a perspective view with the handle raised, and in

Figure 2, a front view, the handle dropped.

This invention consists in the peculiar form and configuration of the sockets and of the handles, which are attached thereto.

The sockets A, B, are composed from leaves, from leaves depending from a knotted loop, the centre of which loop forms the socket, by which the arm B, of the handle C, is attached, the said arms gracefully curved as seen in Fig. 1, and the two united by an ornamental jet handle.

2

05. 2284

I claim the design for a Coffin handle as
herein described and illustrated.
